Primary Examiner — Lauren D McVey*Assistant Examiner* — Justin A Johnson(57) **CLAIM**

The ornamental design for the implantable neural stimulation device, as shown and described.

DESCRIPTION

FIG. 1 is a front perspective of an implantable neural stimulation device showing my new design;

FIG. 2 is a back elevation thereof;

FIG. 3 is a front elevation thereof;

FIG. 4 is a right side elevation thereof;

FIG. 5 is a left side elevation thereof;

FIG. 6 is a top elevation thereof;

FIG. 7 is a bottom elevation thereof; and,

FIG. 8 is a back perspective thereof.

The broken lines illustrate portions of the implantable neural stimulation device and form no part of the claimed design.
